(57) **CLAIM**

The ornamental design for a combined heat cable controller plug and socket, as shown and described.

DESCRIPTION

FIG. 1 is a front perspective view of a combined heat cable controller plug and socket, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The combined heat cable controller plug and socket is shown with a symbolic break in its length. The appearance of any portion of the article beyond the break line forms no part of the claimed design. In the drawings, the broken lines illustrate portions of the combined heat cable controller plug and socket, that form no part of the claimed design.
